(57) **CLAIM**

The ornamental design for a vertical take-off and landing tilt-wing passenger aircraft, as shown and described.

DESCRIPTION

FIG. 1 is a left front top perspective view of a vertical take-off and landing tilt-wing passenger aircraft with landing gear up;

FIG. 2 is a right front bottom perspective view of the vertical take-off and landing tilt-wing passenger aircraft with landing gear up;

FIG. 3 is a front view of the vertical take-off and landing tilt-wing passenger aircraft with landing gear up;

FIG. 4 is a rear view of the vertical take-off and landing tilt-wing passenger aircraft with landing gear up;

FIG. 5 is a right side view of the vertical take-off and landing tilt-wing passenger aircraft with landing gear up;

FIG. 6 is a left side view of the vertical take-off and landing tilt-wing passenger aircraft with landing gear up;

FIG. 7 is a top view of the vertical take-off and landing tilt-wing passenger aircraft with landing gear up;

FIG. 8 is a bottom view of the vertical take-off and landing tilt-wing passenger aircraft with landing gear up;

FIG. 9 is a left front top perspective view of the vertical take-off and landing tilt-wing passenger aircraft, shown in an alternate configuration of use, with landing gear up;

FIG. 10 is a right front bottom perspective view of the vertical take-off and landing tilt-wing passenger aircraft, shown in the alternate configuration of use, with landing gear up;

(Continued)

FIG. 11 is a front view of the vertical take-off and landing tilt-wing passenger aircraft, shown in the alternate configuration of use, with landing gear up;
 FIG. 12 is a rear view of the vertical take-off and landing tilt-wing passenger aircraft, shown in the alternate configuration of use, with landing gear up;
 FIG. 13 is a right side view of the vertical take-off and landing tilt-wing passenger aircraft, shown in the alternate configuration of use, with landing gear up;
 FIG. 14 is a left side view of the vertical take-off and landing tilt-wing passenger aircraft, shown in the alternate configuration of use, with landing gear up;
 FIG. 15 is a top view of the vertical take-off and landing tilt-wing passenger aircraft, shown in the alternate configuration of use, with landing gear up;
 FIG. 16 is a bottom view of the vertical take-off and landing tilt-wing passenger aircraft, shown in the alternate configuration of use, with landing gear up;
 FIG. 17 is left front top perspective view of the vertical take-off and landing tilt-wing passenger aircraft, shown in the alternate configuration of use, with landing gear down;
 FIG. 18 is a right front bottom perspective view of the vertical take-off and landing tilt-wing passenger aircraft, shown in the alternate configuration of use, with landing gear down.
 FIG. 19 is a front view of the vertical take-off and landing tilt-wing passenger aircraft, shown in the alternate configuration of use, with landing gear down;
 FIG. 20 is a rear view of the vertical take-off and landing tilt-wing passenger aircraft, shown in the alternate configuration of use, with landing gear down;
 FIG. 21 is a right side view of the vertical take-off and landing tilt-wing passenger aircraft, shown in the alternate configuration of use, with landing gear down;
 FIG. 22 is a left side view of the vertical take-off and landing tilt-wing passenger aircraft, shown in the alternate configuration of use, with landing gear down;
 FIG. 23 is a top view of the vertical take-off and landing tilt-wing passenger aircraft, shown in the alternate configuration of use, with landing gear down; and,
 FIG. 24 is a bottom view of the vertical take-off and landing tilt-wing passenger aircraft, shown in the alternate configuration of use, with landing gear down.

The broken lines in the drawings depict portions of the vertical take-off and landing tilt-wing passenger aircraft that form no part of the claim.
